G. L. E. KLINGBEIL

SPRING SPREADER FOR VEHICLE SPRINGS

Filed March 7, 1923

Fig. 1.

By Samuel Henick

Attorney

UNITED STATES PATENT OFFICE.

GOTTLIEB L. E. KLINGBEIL, OF OMAHA, NEBRASKA.

SPRING SPREADER FOR VEHICLE SPRINGS.

Application filed March 7, 1923. Serial No. 623,508.

To all whom it may concern:

Be it known that GOTTLIEB L. E. KLINGBEIL, a citizen of the United States, residing at Omaha, in the county of Douglas and 5 State of Nebraska, has invented certain new and useful Improvements in Spring Spreaders for Vehicle Springs, of which the following is a specification.

This invention relates to spring spreaders for vehicle springs and more particularly for automobile springs. It is a well known fact that vehicles and particularly automobiles are rendered "easy riding" and many objectionable squeaks are eliminated 10 if the springs are properly lubricated from time to time. However, this work is frequently neglected by the owner of the automobile because of the difficulty of separating the leaves of the springs. For the same 15 reason the cost of having this work done at a garage is considerable. The object of the present invention is to provide a spring spreader constructed in such manner that by a single movement of an operating handle 20 all of the leaves of a spring will be separated simultaneously and automatically held in such separated condition during the time that they are being lubricated or otherwise worked upon.

30 A spring spreader possessing the foregoing characteristics is illustrated in my copending applications Serial Numbers 586,775 and 586,776 filed on the 7th day of September, 1922, and the present application is intended to cover certain improvements in the construction illustrated in the foregoing application.

These improvements relate to the following features of the invention:

40 A—An improved manner of supporting the wedge assembly;

B—An improved way of adjusting the lateral tilting of the standards so that finer adjustment may be secured than was possible with the old construction; and

C—Means for mounting the lower ends of the standards for movement toward and from each other.

In other words the pivots upon which the 50 standards swing are mounted for bodily adjustment toward and from each other to adapt the device to take care of springs which vary widely in width, this feature rendering it possible to take care of such 55 widely varying springs while at the same time it brings the standards in positions of

substantial parallelism with each other when their upper ends are moved toward each other in separating the leaves of a spring.

Further objects and advantages of the 60 invention will be set forth in the detailed description which follows.

In the accompanying drawing: Fig. 1 is a view partly in side elevation and partly in longitudinal section of a spring spreader 65 constructed in accordance with the invention; Fig. 2 is a perspective view of the upper part of one of the standards of the spring spreader; and Fig. 3 is an end view of the base. Like numerals designate corresponding parts in all of the figures of the drawing.

The present device like the device shown in my copending application above referred to comprises a base 5 in which a tilting block 75 6 is mounted. Substantially vertical standards 8 and 9 are pivoted in the tilting block by pivots 51 and 52. The upper ends of these standards are moved toward and from each other by a self-locking mechanism 80 which consists of a transverse shaft 12 mounted in upstanding portions 13 of the tilting block 6 and provided with an angular end 14 for the reception of a handle or other suitable tool by which a partial turning movement may be imparted to the shaft. The shaft 12 carries cranks 15, to the outer ends of which bent links 16 and 17 are pivotally connected at 18 and 19, respectively. The outer ends of these bent links are pivotally connected at 20 and 21 to the lower 90 ends of levers 22 and 23. These levers, in turn, are pivotally connected at 24 and 25 to the standards and said levers at their upper extremities are pivotally connected at 26 and 27 to the cross links 28 and 29, respectively. The link 29 is pivotally connected at 30 to the standard 9 and the link 28 is pivotally connected at 31 to the standard 8. Thus it will be seen that if a turning movement is 100 imparted to the shaft 12 by the application of the proper tool to the angular head 14 of said shaft and the bent links 16 and 17 be thrown to the position illustrated in Fig. 1 the standards will be forcibly moved toward each other, due to the levers 22 and 23 acting directly upon the standards at pivot points 24 and 25 and upon the opposed standards through the crossed links 28 and 29. It will further be seen that the standards will remain in the position to which 110 they are moved when they are brought forci-

bly together due to the fact that with the parts in the position illustrated in Fig. 1 a line drawn from pivot point 19 to pivot point 21 lies below the center of the shaft 12. In other words that portion of the crank 15 which acts upon the link 17 has been moved to past center position and the same is true with respect to link 16 and that part of the crank which acts upon it. The upper portions of the standards are slotted, as indicated at 35 for the reception of wedge assemblies, said wedge assemblies being bodily insertible in the upper portions of the standards as units.

The purpose of arranging the parts in the manner described is to render it possible to easily and quickly place different wedge assemblies in position according to the size, width and thickness of the springs which are to be acted upon. Cars of many different makes are brought to public garages to have their springs lubricated. Thus it is necessary to provide, in an article of this nature, means for readily adapting it to take care of the different sizes of springs. To this end I provide the wedge assemblies consisting of bolts 36. These bolts pass through elongated openings 38 formed in a plurality of wedge elements 39.

In my copending application referred to, plates 42 through which the bolts 36 pass merely rested upon the upper ends of the standards. In the present construction, I employ corresponding plates 42 but I notch these plates at their forward corners, as indicated at 42^a, and extend the front corner portions of the standards upwardly into said notched portions as at 42^b so that an interlocking engagement between the plates 42 and the standards is brought about. The wedge elements 39 are provided with shoulders 43 which rest against the front faces of the portions of the standards which lie upon opposite sides of the slotted portions thereof and which take the rearward thrust of these wedge elements and relieve the bolts of this strain. The lower ends of the bolts are reduced, as indicated at 44 to enter openings 45 formed in the standards. A plate 46 having a rounded upper face 46^a is mounted upon the lower portion of each of the bolts and the rounding of the upper face of this plate facilitates tipping movement of the wedge elements as they individually seek to come to a position of rest with their pointed inner ends engaged in the grooves between the leaves of the springs to be spread. I preferably dispose a spring 48 between plate 46 and the bottom of the bifurcated portion of the standards. By thrusting bodily downward upon the top of these bolts the group of wedges may be given a limited vertical movement as a whole to bring about a coarse adjustment of the vertical position of the several wedge elements. Capability of the wedge elements of individual movement permits the several wedge elements to seek a position of rest with their pointed inner ends engaging in the grooves between the leaves of the springs as hereinbefore stated.

In my application aforesaid the block 6 is shown mounted upon short trunnions. In the present case I utilize as trunnions bolts 50 having eyes at their inner ends which eyes engage the pivots 51 and 52 upon which the lower ends of the standards 8 and 9 are mounted. The sides of the block 6 are longitudinally slotted, as indicated at 53 and 54 and it is manifest that by longitudinally adjusting the bolts the pivots of the standards may be adjusted toward and from each other. To effect this longitudinal adjusting of these pivots with accuracy, the outer ends of the bolts are threaded, as indicated at 55 for the reception of lock nuts 56 and 57. These lock nuts lie upon opposite sides of upwardly projecting portions 58 of the base 5. These lock nuts serve to lock the pivots 51 and 52 in their adjusted position longitudinally of the block 6 and to lock the standards in lateral tilting position after they have been adjusted to the particular inclination of the spring upon which the device is being used. I employ a stud 59 which is carried by an upstanding portion 60 of the block 6. This stud moves in an arcuate slot 61 of an upstanding end 62 of the base 5 and is adapted to be bound in varying positions of adjustment in the length of said slot by means of a lock nut 63.

It is manifest that through the several adjustments specified the device may be used to spread the leaves upon a wide variety of springs irrespective of their particular width or inclination and while they are in place upon the machine.

A device of this character is particularly intended for use in garages where it provides means for expeditiously spreading the leaves of the springs simultaneously. This saves a great deal of time and work and in addition assures that a thorough job of lubricating the springs may be performed.

It is to be understood that the invention is not limited to the precise construction set forth but that it includes within its purview whatever changes fairly come within either the terms or the spirit of the appended claims.

Having described my invention what I claim is:

1. In a device of the character described comprising a base, a pair of standards pivot-ed thereon for swinging movement toward and from each other, means for forcibly moving said standards toward each other, spring leaf spreading means carried by said standards, longitudinally disposed bolts en-

gaged with the pivots of said standards and means for adjusting said bolts longitudinally with respect to the base.

2. A device of the character described comprising a base, a pair of standards pivotally mounted thereon for swinging movement toward and from each other, means for forcibly moving said standards toward each other, spring leaf spreading means carried by said standards and means for longitudinally adjusting the pivot points of said standards towards and from each other comprising bolts having eyes engaged with said pivots and lock nuts on said bolts and means carried by the base and engaged by said lock nuts whereby the bolts may be adjusted longitudinally with respect to the base under the action of said nuts.

3. A device of the character described consisting of a base comprising a tilting block; means for holding said block in varying positions of lateral tilting with respect to said block, standards having their lower ends pivoted in the tilting block and means for adjusting the pivots of said standards in said block and longitudinally of the block, said means comprising bolts engaged with the pivots of the standards and means for adjusting said bolts longitudinally with respect to the base.

4. A structure as recited in claim 3 wherein the means for adjusting the lateral tilting of the tilting block comprises a stud, and an upstanding member upon the base having an arcuate slot in which said stud travels and a binding element upon the stud.

5. A device of the character described

comprising a base having upstanding members therein, a tilting block, bolts having portions extending into said blocks and passing through said block and through said upstanding members to thereby constitute trunnions for the block, means for adjusting the bolts longitudinally and means for engaging said bolts with the pivots of the standards.

6. A structure as recited in claim 5 in combination with lock nuts upon said bolts and upstanding members upon the base with which said lock nuts are adapted to engage.

7. A device of the character described comprising a pair of standards, wedge assemblies comprising vertical bolts and plates through which said bolts pass and means constituting interlocking elements between the plates and the opposite sides of said standards.

8. A device of the character described comprising a pair of standards each of which is slotted from front to rear at its upper end to constitute a part open front and rear, wedge assemblies seated in said slotted parts and comprising vertical bolts, plates through which said bolts pass, said plates having their forward corners notched out and members upon the opposite sides of said standards projecting into said notched out portions of the plates.

In testimony whereof he affixes his signature in the presence of two witnesses.
